UNITED STATES PATENT OFFICE.

PAUL PIGNOT, OF YONKERS, NEW YORK, ASSIGNOR TO ALEXANDER SMITH
& SONS CARPET COMPANY, SAME PLACE.

DESIGN FOR A CARPET.

SPECIFICATION forming part of Design No. 13,988, dated June 19, 1883.

Application filed May 4, 1883. Term of patent 3½ years.

To all whom it may concern:

Be it known that I, PAUL PIGNOT, of Yonkers, Westchester county, New York, have invented a new and original Design for Carpets, 5 of which the following is a specification.

The accompanying photograph illustrates my new design for carpets.

This invention relates to a new design for carpets, oil-cloths, and analogous fabrics; and 10 it consists of the new ornamentation of parts, hereinafter more fully pointed out.

On the background of the carpet is the representation of a tree, A, not far from which stands another tree, B, the ground in front of

these trees being covered with floral plants C, 15 that are arranged in picturesque order, leaving the free space D between the floral decorations and said trees, to give to the entire design the effect of a landscape in midsummer.

I claim—

The design for carpets, consisting of the tree-like figures A B, floral figures C, and space D, substantially as shown.

PAUL PIGNOT.
